UNITED STATES PATENT OFFICE.

CHESTER A. RASMUSSEN, OF LONG BEACH, CALIFORNIA, AND WILLIAM H. RINEHART,
OF WAYNESBURG, PENNSYLVANIA.

VALVE MECHANISM FOR INNER DRILL-CASING TUBES.

Application filed March 20, 1924. Serial No. 700,564.

Our invention relates to drill casing with inner tubes and a valve mechanism to close the annular space between the tube and the casing and also to close the upper end of 5 the inner tube.

In drilling wells it has been found that if an inner tube is used within the drill tube or casing which operates the drill, that in case the drill tube breaks or separates, the 10 inner tube, being attached to the drill, will hold it and enable the operators to withdraw the drill out of the well with the upper part of the drill casing. In normal operation the water is pumped down the drill casing 15 and into the upper end of the inner tube and to the drill. In case the drill casing parts and the upper portion is moved relative to the inner tube, by our invention the openings into the inner tube are closed and 20 the space around the inner tube is closed and the upper end of said drill casing is filled with water and makes it difficult to remove the casing from the well, and also makes a very disagreeable task because of 25 the water in the casing above the inner tube.

Among the salient objects of our invention are, to provide means for automatically opening the upper end of the inner tube when the outer or drill casing has parted 30 by turning said outer or drill casing, its movement relative to said inner tube operating to uncover the openings into the inner tube and thereby allow the water in the upper end of the drill casing to run down into 35 said inner tube; to provide in a device of the character referred to means for holding the inner tube within the drill casing and for closing the annular space between the inner tube and the drill casing; and, in general, 40 to provide an improved valve or shut off mechanism between an inner tube and an outer drill casing.

In order to explain our invention, we have 45 illustrated one practical embodiment thereof on the accompanying sheet of drawings which we will now describe.

Figure 1 is a longitudinal sectional view through an inner tube and an outer drill casing, showing our invention, also in section;

Figure 2 is a cross sectional view on line 2-2 of Fig. 1;

Figure 3 is a cross sectional view on line 3-3 of Fig. 1; and

Figure 4 is a side elevation of the valve 55 cap forming part of the invention.

Referring now to the drawings in detail, 1 designates a drill case, with a two-part coupling composed of the parts 2 and 3, the upper part of the drill case being 60 screwed into the upper end of part 2 of the coupling, and the lower part of the drill case being screwed into the lower end of the part 3 of the coupling, and part 3 of said coupling being screwed into the lower end 65 of part 2 of said coupling, substantially in the manner indicated. The upper end of the part 3 of said coupling is of thicker construction and forms an annular shoulder, as at 4, around which is a packing ring, 5, for 70 a purpose hereinafter again referred to. In the upper part 2 of said coupling, are provided inwardly projecting elements, as 6, 6, projecting into the annular space between the inside of said coupling and an inner 75 tube, 7, said inner tube 7, fitting through the lower part 3, of said coupling, substantially in the manner indicated. Said inner tube 7 is provided with a series of openings, as 7^a, 80 and at its upper end is provided with an intermediate member, 8, screwed thereupon, its outer end being reduced in diameter and provided with a left-hand thread, 8^a, over which is screwed a closure or cap, 9, shown in side elevation in Fig. 4, and provided on 85 its opposite sides with tapered ears, 9^a, 9^a, substantially as shown.

In operation, the parts are in substantially the positions shown, as the drill case 1 is turned for operating the drill at the lower 90 end of the drill case, in the usual manner, water being forced down through the upper part of said well or drill case and into the upper end of the inner tube 7. In case the drill case 1 breaks, or becomes uncoupled, 95 the continued rotation thereof will cause a relative movement of the tube and case, said inner tube moving down, or the drill case moving up, until the lower end of the intermediate member 8, rests upon the packing 100 member 5, the openings 7^a passing down into the upper part of the part 3 of the coupling, whereby to cut off said openings and thus prevent water from passing down into the inner tube from the upper part of said 105 drill case. The side ears, 9^a, 9^a, being pointed pass the projections 6, 6, and stop opposite them, whereupon continued rota-

tion of the drill case 1, operates to turn the closure or cap 9, off the intermediate member 8, or partially off, and sufficient to uncover the openings 8^b in the upper part of said intermediate member 8, as indicated, thus allowing the water from the upper part of the case 1, above the inner tube, to run down through said openings 8^b, into said inner tube and out at the lower end.

10 Thus we have provided an inner tube with a closure member which can be operated to open access to the inner tube by the relative movement of the drill case, and with means for closing the annular space between the inner tube and said drill case. It is to be understood, of course, that with the parts in the positions shown in solid lines, Fig. 1, the pump can force the water and liquid down through the upper part of the drill case 1, and through the openings 7^a in the inner tube and on down to the drill head. In case the drill case 1 should be parted or disconnected down in the well, its movement relative to the inner tube 7, would cause the inner tube 7 to close the annular space by reason of the intermediate member 8, resting on the packing 5, on the annular shoulder 4, of the member 3. With this annular space thus closed, the pump cannot force the water down through the drill case and the pump is, therefore, stopped. This indicates that the drill case has been parted or disconnected down in the well. By turning the drill case, as hereinbefore described, the closure member 9, can be removed, and thus again permit the water and fluid from the upper part of the drill case 1 to run down into the inner tube, through the openings 8^b, in the intermediate member 8, as before described.

We do not limit our invention to the showing made for the purposes of explaining it, except as we may be limited by a broad interpretation of the hereto appended claims forming a part of this specification.

We claim:—

1. In combination, an outer drill casing having an inwardly projecting element, an inner casing, a packing therebetween, said inner casing having inlet openings near its upper end above said packing, a closure member for said inlet openings, adapted to be moved to open and close said openings, said closure member being adapted to be moved by the inwardly projecting element in said outer casing when said outer casing is moved longitudinally and rotatively relative to said inner casing.

2. In combination, an outer drill casing having an inwardly projecting element, an inner tube having openings at its upper end, whereby liquid in said outer casing above said inner tube can enter said inner tube, a packing between said casing and tube below said openings, a closure member for said

openings on said inner tube, said closure member being rotatable to open and close said openings, and means on said closure member adapted to be engaged by the projecting element in said outer casing for engaging and moving said closure member to open said openings, when said outer casing is moved longitudinally and turned relative to said inner tube.

3. In combination, an outer drill casing, an inner tube having its upper end open to receive liquid from the outer casing, a closure member for said inner tube adapted to close the open end thereof, a packing between said casing and tube below said opening and means whereby the movement of said outer casing longitudinally and rotatively relative to said inner tube operates to move said closure member to open said opening to permit liquid from said casing to enter said inner tube.

4. In combination, an outer drill casing, an inner tube having openings through its side near its upper end, a closure member over said end and adapted to be turned to uncover said openings in the side of said inner tube, packing means between said casing and tube and means on said outer casing adapted to engage and turn said closure member when said outer casing is moved longitudinally and turned relative to said inner tube, substantially as described.

5. In combination with a drill case, a coupling therein forming an inner annular shoulder, an inner tube therethrough, packing therebetween, closure means on the upper end of said inner tube, said closure member being adapted when said tube and said drill case are moved relative to each other longitudinally to engage with said annular shoulder and to close the annular space between said inner tube and said coupling and means whereby rotation of said casing opens said closure member.

6. In combination, a drill case having a coupling with means therein providing an inner annular shoulder, a packing ring on said shoulder, an inner tube therethrough, a closure member on the upper end of said tube adapted to rest upon said packing on said annular shoulder when said tube and drill case are moved relative to each other, the upper end of said tube being closed with a removable member and means whereby rotation of said casing opens said closure member.

7. In combination, a drill case, a coupling therefor having an inner annular shoulder, a packing on said shoulder, an inner tube fitting through said annular shoulder, an intermediate member on the upper end of said inner tube and adapted to engage with said packing when said inner tube and said drill case are moved relative to each other, a closure member on said intermediate mem-

ber and means whereby rotation of said casting opens said closure member.

8. In combination, a drill case, a coupling therefor providing an inner annular shoulder, a packing on said shoulder, said coupling having inwardly projecting elements, an inner tube through said annular shoulder having openings through its side above said shoulder, an intermediate member screwed 10 on to the upper end of said tube and adapted to engage said packing on said annular shoulder when said tube and case are moved relative to each other, a closure member screwed onto said intermediate member with 15 reverse screw threads to those connecting said intermediate member to said inner tube, and means on said closure member adapted to engage with said inwardly projecting elements, whereby rotative movement of said 20 drill case operates through said projecting elements to unscrew said closure member to open communication with the upper end of said inner tube, substantially as described.

9. In a device of the character shown and

described, in combination, a drill case, a two 25 part coupling therefor, one part providing an inner annular shoulder, a packing element on said shoulder, inwardly projecting means on one part of said coupling, above said shoulder, an inner tube through said 30 shoulder and packing, said tube having openings through its side above said packing, an intermediate member screwed onto the upper end of said inner tube, a closure member screwed on to said intermediate 35 member with a left hand screw, and projections on said closure member adapted to engage with said inwardly projecting means whereby longitudinal and rotative movement of said drill case relative to said tube 40 operates to unscrew said closure member to uncover inlet openings to said inner tube.

Signed at Los Angeles, Los Angeles County, California, this 8th day of March, 1924.
